CLAIM

The ornamental design for a support element of a protective cover for a mobile computing device, as shown and described.

FIG. 10 is a top view of the embodiment of support element illustrated by FIGS. 1 through 9, in the position depicted in FIG. 9;

FIG. 11 is a bottom view of the embodiment of support element shown in FIGS. 1 through 10, in the position illustrated by FIGS. 9 and 10;

FIG. 12 is a first side view of the embodiment of support element depicted by FIGS. 1 through 11 in the position shown in FIGS. 9 through 11;

FIG. 13 is a second side view of the embodiment of support element depicted by FIGS. 1 through 12 in the position illustrated by FIGS. 9 through 12;

FIG. 14 is a top view of the embodiment of support element illustrated by FIGS. 1 through 13, in the position depicted by FIGS. 1 through 8, showing the support element as part of an embodiment of a protective cover for a mobile computing device; and,

FIG. 15 is a top view of the embodiment of support element illustrated by FIGS. 1 through 13, in the position depicted by FIGS. 9 through 13, showing the support element as part of an embodiment of a protective cover for a mobile computing device.

Broken lines have been included in the drawings merely to illustrate examples of environments for the embodiment of design for the support element depicted in the drawings. The features that are illustrated by broken lines form no part of the claimed design.

The claimed design may be arranged in a plurality of positions and, therefore, is not limited to the positions illustrated by the drawings.
